(57) **CLAIM**

The ornamental design for a light switch shaped flashlight, as shown and described.

DESCRIPTION

FIG. 1 is a top plan view of the light switch shaped flashlight showing my design;

FIG. 2 is a bottom plan view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a front perspective view thereof;

FIG. 8 is another front perspective view thereof showing the switch in the pressed position; and,

FIG. 9 is an exploded perspective view thereof showing the cover separated from the main body.

The phantom lines shown in the FIG. 9 are illustrative of environmental structure only and form no part of the claimed design.
